B. J. RABIN

CHEESE CUTTING DEVICE

Filed Feb. 27, 1925

INVENTOR

Benjamin J. Rabin
George Freeman
ATTORNEY

UNITED STATES PATENT OFFICE.

BENJAMIN J. RABIN, OF NEW YORK, N. Y.

CHEESE-CUTTING DEVICE.

Application filed February 27, 1925. Serial No. 11,961.

This invention relates to apparatus for cutting soft cylindrical bodies, such as cheeses, into segment portions of uniform weight and has as one of its features the provision of a simple easily operated device for attaining such results.

It is well known in the art that thin wires have been used as the cutting elements, these wires being tensionally strained to act effectively and it is further known that such wires frequently break while being used for cutting semi-hard cheese causing delay and vexation.

In order to overcome the tendency of disruption of the wires, springs have been used at the ends of the wires to absorb a portion of their stress when bent into a catenary form during operation, but such expedients in themselves have proven ineffective and particularly so for cutting Roquefort cheese.

It is therefore an object to provide an apparatus using wires as cutters and to so mount the wires that breakage is practically eliminated.

It is a further object to provide in an apparatus using wires as cutters, adjustable means for varying the angular relation of the wires to produce cuts of uniform, bulk or weight though of varying dimensions.

These aims and objects are accomplished by the novel construction and combination of parts, hereinafter described and shown in the accompanying drawing, forming a material part of this disclosure, and in which:—

Figure 1 is a top plan view of an embodiment of the invention, the cutter head suspending elements being omitted.

Figure 2 is a front elevational view showing a complete assemblage of the same, parts being in section to disclose the structure.

Figure 3 is a detail, and

Figure 4 is a plan view of a modification.

The apparatus as shown on the drawing comprises a rigid base plate 10 having at its center a block 11 containing radial grooves 12 in its face or upper surface on which may be placed a cheese 13 of the usual squat cylindrical shape.

A pair of upright standards 14, are firmly secured in the base 10 and slidably mounted on the standards is a frame generically denoted by the numeral 15, comprised of upper cross bars 16 secured by fastenings 17 to transverse bars 18 having cross members 19.

This frame is pendantly supported by 55 eyes 20 in which are engaged flexible elements 21 leading from the four corners of the frame to a ring 22, in turn supported by elements 23, connected to a cable 24, trained over sheave pulleys 25 and 26, the 60 depending end of the cable being attached to a counter-weight not shown.

Guided by the pins 17, which project downward from the frame, is a ring 27 held against the underside of the frame members 18 and secured at equal distances apart are a plurality of strong but fine wires 28 crossing each other at the center of the apparatus and having their opposite ends secured in eyes 29 formed on bolts 30 which pass 70 through the ring at diametrically opposite points, to be encircled by coiled compression springs 31 held stressed by thumb nuts 32 threaded on the projecting ends of the bolts, 75 as best seen in Fig. 3.

A second ring 33 is held removably against the under surfaces of the bars 18 and elements 19, this ring being provided in its lower edge with slots 34 acting as guides and supports for the wires 28, taking the 80 thrust and strain of cutting and preventing breakage as experience has demonstrated.

The slots 34 are spaced equidistant so that when a cheese having a circular cross section is cut, the segments will be of equal 85 size and hence of substantially equal weight. However, if a cheese be oval or irregular in cross section instead of circular, then ring 33^a may be substituted for ring 33. Ring 33^a is provided with slots 34 spaced unequally so that the angular relation of the wires in one direction, may differ from the angular relation in another direction in such a way that while the segments cut from the cheese may vary in size, they will be substantially equal in weight. In practice, a variety of rings 33^a may be kept on hand, each having its slots 34 differently spaced.

In operation, the proper ring 33^a or ring 33 is attached to the frame and the wires placed in slots 34, the cheese 13 is placed substantially concentric on the block 11, the cutter head being at that time raised on the standards 14; thereafter pressure is applied on the frame, forcing the wires to enter and pass through the cheese eventually entering the grooves 12 in the block.

Due to the pressure applied by the inner

guiding ring 33, the strain on the cutting wires is equalized, making an effective and substantially unbreakable slicing apparatus for the purpose indicated.

Although I have described my improvements with considerable detail and with respect to certain particular forms of my invention, I do not desire to be limited to such details since many changes and modifications may well be made without departing from the spirit and scope of my invention in its broadest aspect.

Having thus described my invention what I claim as new and desire to secure by Letters Patent, is:

1. In a cutting apparatus, a head composed of bars arranged in the manner of an open frame and carrying relatively large and small rings, cutting wires fixed at their ends in the larger ring to extend diametrically across, said wires being guided and pressed by the smaller ring at points intermediate their lengths, and means for resiliently tensioning each of said wires, said means being independently adjustable.

2. A cheese cutting apparatus to divide the cheese into segmental portions of approximately equal bulk simultaneously, com-

prising a base having offset standards, a head 30
slidable on the standards, a ring fixed on
said head, a plurality of cutting wires fixed
in said ring at equal distances apart and
crossing each other at the center, and selective
means intermediate the lengths of said
wires to alter the angular relation thereof,
said means also serving to prevent breakage
of said wires.

3. The combination in a cutting apparatus
of a vertically movably head, a large ring
fixed to said head, cutting wires fixed at
their ends in said ring to extend diametri-
cally across, and selective means inter-
mediate the lengths of said wires adapted
to guide the wires to produce segments of
equal bulk though of unequal dimensions of
an article to be divided.

4. The combination with a cutter head
having radial cutting wires of selective
means intermediate the length of said wires
adapted temporarily to alter the angular
relation of said wires.

Signed at New York, in the county of
New York and State of New York this 5th
day of February 1925.

BENJAMIN J. RABIN.
